Buyers, Cavanaugh, Whitehead & Hyde

UNITED STATES PATENT OFFICE.

MAX ZWICKL, OF HOBOKEN, NEW JERSEY.

AUTOMOBILE HEATER.

1,420,301.

Specification of Letters Patent. Patented June 20, 1922.

Application filed April 11, 1921. Serial No. 480,449.

To all whom it may concern:

Be it known that I, MAX ZWICKL, a citizen of the United States, and resident of Hoboken, in the county of Hudson and State 5 of New Jersey, have invented certain new and useful Improvements in Automobile Heaters, of which the following is a specification.

My invention relates to improvements in 10 heating apparatus for motor vehicles, and is particularly directed to improvements in apparatus employing the heat of the exhaust gases for this purpose.

Devices of this kind heretofore employed 15 have generally been of one of two types. A large number have employed the hot gases directly as the heating medium, ordinarily passing them through suitable radiators. This type of heater, however, is inoperative 20 when the engine is not run; and it has been found that in really cold weather it became necessary to run the engine when the car was standing still in order to prevent the interior of the car from becoming chilly.

In order to avoid the waste of fuel 25 resultant upon this practice, it has heretofore been proposed to employ water as the heating medium, the exhaust gases being utilized for heating the water. While systems of 30 this type retain their heat for a considerable length of time after the engine has stopped, they are subject to two principal disadvantages.

For one thing, it takes a substantial length 35 of time for the water to become heated, so that with this type of system a considerable period must elapse after the engine is started before the car becomes adequately warm. Furthermore, in these systems the water is 40 not sufficiently hot to heat the car adequately in extremely cold weather, particularly when there is a heavy wind or when the car door is opened very frequently.

A principal object of my invention is to 45 provide a motor vehicle heating apparatus which will combine the advantages of the hot water system above referred to, particularly in its capacity to retain its heating properties to a substantial degree for a considerable period after the motor has been 50 stopped, without being subject to the limitations in heating capacity from which systems of the hot water type suffer.

I accomplish this object by employing a 55 system in which water may be heated to a point where it forms steam, so that the wa-

ter and steam will retain the heat, while the steam may be raised to any desired temperature.

There are numerous difficulties in the provision of a heater of the type indicated in which steam may be generated, such as the limited amount of water which the heat available from the average engine will convert into steam, and the provision of a radiating system in which the greatest amount of heat will be obtained from the water and steam without such a reduction in temperature in the heater as to make the generation of steam impossible. I have devised a 70 heating apparatus which overcomes these disadvantages, and which accomplishes the further objects of ready installation and ease of manufacture.

A further object is the provision of a 75 heater of the type indicated which is adapted to muffle the exhaust gases at the same time that the heat is obtained therefrom. I have also devised a steam heater so arranged that the temperature may be readily controlled.

A subsidiary object is the provision of a heater in which the temperature may be readily shown by an indicator located at a distance, as on the instrument board of the 85 usual motor vehicle, without expensive or complex thermometers or analogous devices. I accomplish this object by providing a steam pressure gauge connected to the heater, the pressure of the steam being of course directly related to its temperature.

Other objects and advantages of my invention will be apparent from the following description taken in connection with the accompanying drawings, in which:

Fig. 1 is a diagrammatic side view of one exemplification of my invention installed in a motor vehicle,

Fig. 2 is an enlarged perspective view of the heater installed beneath the front seat 100 of a vehicle, and

Fig. 3 is a vertical sectional view of the heater proper taken along radial planes passing through the various inlet and outlet devices, the position of which is somewhat varied from that of Figs. 1 and 2.

My heater includes a relatively small body portion adapted to contain the water employed, and having a plurality of conduits passing through the water space through which the exhaust gases pass, the conduits being so constructed and arranged that the

water is heated by radiation therefrom, and the gases are muffled at the same time.

A convenient form of heater body includes a shell 10 closed at the top by plate 11 and at the bottom by plate 12. A plurality of exhaust gas conduits in the form of flues 13 extend through the interior of shell 10 and fit tightly into suitable openings in plates 11 and 12. The exhaust gases are led through flues 13 in such a way that they will pass upwardly through a number of the flues, and downwardly through the remainder, so as to heat the water 14 and at the same time muffle the gases. One convenient arrangement for this purpose includes the provision of an inlet chamber 15 communicating with one end of the flues 13 through which the gases pass upwardly, an outlet chamber 16 communicating with the corresponding end of the flues through which the gases pass downwardly, and an upper chamber 17 through which the gases may pass from the up to the down flues, the change in direction in chamber 17 helping to produce the muffling effect. Chamber 15 is connected with the engine exhaust, as by means of pipe 15^a, and chamber 16 preferably connects with a pipe 16^a extending rearwardly to a point adjacent that of the usual exhaust discharge. If desired, this effect may be assisted by properly proportioning the up and down flues, or by varying the number of flues of each kind; but my device has been found to operate satisfactorily where the flues communicating with chambers 15 and 16 are of approximately the same size and number.

While it is of course understood that I am not necessarily limited to the exact physical construction disclosed, an extremely convenient and cheap construction of the type described is provided by forming chambers 15 and 16 from a single dished casting having a marginal flange 18 adapted to be mounted on the floor of the car, with a central partition 19 to divide chambers 15 and 16. The upper chamber 17 may be formed in a hollow head 20, and the whole heater may be held in assembled position by means of bolts 21 threaded into or otherwise engaging the bottom of chambers 15 and 16, and provided with nuts 22 screwing down on the top of head 20. For convenience in construction, bolts 21 may pass through flues 13, thereby simplifying the construction of the heater. It will be apparent that by releasing nuts 22 the various parts of the heater heretofore described may readily be separated and cleaned or replaced, the exact extent and method of separation being somewhat dependent upon the precise form of the parts employed, which may be varied considerably by one skilled in the art.

For one thing, plates 11 and 12 and flues 13 may be constructed and connected in the

usual way for making boiler flues; though this is not essential. Furthermore, plates 11 and 12 may be separate from or connected to the shell 10 and head 20, as desired.

To obtain the maximum efficiency of my heater, I have found it desirable to fill it with water 14 up to about the half-way point, leaving a steam space 23 above the water. Any suitable means for filling the heater with water may be provided, such as the filler pipe 24 mounted on and passing through a wall of the shell 10 and covered by a screw cap 25. An air vent 26 is preferably provided for permitting the air to escape during filling, vent 26 preferably being controlled by a valve as illustrated. I also preferably provide means for draining the tank without taking it apart, a convenient arrangement of well-known type being disclosed, including the drain pipe 27 controlled by valve 28 and discharging through the floor of the vehicle. It will be noted that various arrangements of these elements are shown in the three figures, and various other methods of arrangement and construction may obviously be employed.

Manifestly the size and shape of my heater may be varied within wide limits, depending upon the construction of the car and the location of the heater. In any event, however, it is desirable to have the heater fairly small in size, not only because of the increased facility with which steam is generated, but also for economy of space in the car. With a great many standard types of car the heater may readily be mounted on the car floor in a recess 29 in the back of the front seat 30, as shown in Fig. 2, where it may be arranged so that a door 31 may be closed to hide the heater when not in use.

I may provide means of any well-known type for driving as much of the exhaust as is desired into the heater. For this purpose, the pipe 15^a may be connected to the usual exhaust pipe 32, with a valve 33 controlled by handle 34 adapted to regulate the opening of pipe 15^a to control the flow of exhaust gas therein. The valve 33 may be located at the junction of pipes 32 and 15^a, so that it will close either of these pipes proportionately as the other pipe is opened. In this way the heat may be readily regulated. This feature, however, is not an essential part of my invention, and any means may be provided for regulating the flow of exhaust gas through pipe 15^a.

In order to enable the operator to see at a glance the temperature of the heater, I may employ a steam gauge 35 on the instrument board of the car connected with the steam space 23 of the heater by a small pipe 36. The steam space should also be connected to a safety valve 37 which may be conveniently mounted on pipe 36, and which may be set for any desired pressure in accord-

ance with the maximum heat required in the car. This will provide an automatic limit to the radiator temperature, as well as prevent damage through the generation of excess pressure in the heater.

5 It will be evident that in the embodiment shown, I have provided a heater of simple construction which may be readily controlled, and whose heating effect may be directly observed by the operator through the 10 employment of steam gauge 35 without requiring the use of any thermometer or similar instrument. It should, of course, be kept in mind that the temperature adjacent the 15 heater may be entirely different from that where the driver sits, as the latter part of the car may be partitioned off from the rear portion, or air circulation in the front of the car may render it decidedly cooler than the rear part. For this reason an ordinary 20 thermometer showing the car temperature and located adjacent the driver would in many cases be inadequate. It has also been found in actual practice that with the heater 25 constructed as shown, the muffling effect is fully as great as that of the standard type of muffler, the engine making no more noise and being subjected to no more back pressure when the gases are passing through the 30 heater than when they pass through the usual muffler.

While I prefer the form of heater shown, in which the water and steam radiate heat directly from the walls of the heater, and 35 where the heater is itself mounted in the body of the car, obviously my invention is not necessarily restricted to these features, since it is well known in the art to locate the heater outside of the car body and to 40 convey a heated fluid into the car, either directly as when hot air is employed, or through a suitable pipe system as when another fluid is used; and these principles could be applied to my heater by one con- 45 versant with this art.

While my heater in its broad aspect is essentially adapted for the specific use designated, it will be apparent that certain of the more detailed features are equally applicable 50 to heaters for other purposes.

I claim:

1. A steam heater for motor vehicles, including a tubular water reservoir having separate inlet and outlet chambers at one 55 end and a transverse chamber at the other, a plurality of pipes connecting the inlet chamber with the transverse passage, a plurality of pipes connecting the transverse passage with the outlet chamber, and means 60 for conducting motor exhaust gases to the inlet chamber.

2. A steam heater for motor vehicles, adapted to be mounted within a vehicle, including a tubular water reservoir of relatively small size adapted to radiate heat;

a reservoir head having a closed chamber extending substantially across the reservoir, a base for the reservoir including a pair of separate chambers which together extend across substantially the entire bottom 70 of the reservoir, one of said chambers being adapted for connection to a motor exhaust and the other adapted to provide an outlet for exhaust gases, a plurality of longitudinal pipes in the reservoir connecting the exhaust-connected chamber in the base with the transverse chamber in the head, and a plurality of longitudinal pipes in the reservoir connecting said chamber in the head with the outlet chamber in the 80 base, the construction being such that steam is generated from water in the reservoir, and the exhaust is muffled, during the passage of exhaust gases through said pipes and chambers. 85

3. A steam heater for motor-vehicles, comprising a tubular water jacket, a hollow header at one end of the jacket divided by a partition into a gas intake and a gas outlet chamber, an undivided hollow header 90 at the other end of the jacket, a plurality of gas tubes passing through the jacket and connecting the headers, some of the tubes communicating with said intake chamber and others communicating with said outlet chamber, a connection for engine exhaust 95 gas to said intake chamber, and a discharge connection for said outlet chamber.

4. A steam heater for motor-vehicles, comprising an upright tubular water jacket, 100 a hollow header at the bottom of the jacket divided by a partition into a gas intake and a gas outlet chamber, an undivided hollow header at the top of the jacket, a plurality of gas tubes passing through the jacket and 105 connecting the headers, some of the tubes communicating with said intake chamber and others communicating with said outlet chamber, a connection for engine exhaust 110 gas to said intake chamber, and a discharge connection for said outlet chamber.

5. In a combined steam heater and exhaust muffler for internal-combustion motor vehicles, the combination of a dished base having a transverse partition defining exhaust-gas intake and discharge chambers, a gas connection for each chamber, a tubular water jacket having a bottom plate adapted to close the open top of said base and also having at its upper end a hollow 115 header, a plurality of gas tubes running longitudinally through the jacket and connecting the header with said bottom plate, some of said tubes communicating with said intake chamber and others communicating 120 with said discharge chamber, and means for detachably connecting the jacket to the base.

6. In a combined steam heater and exhaust muffler for internal-combustion motor 130

vehicles, the combination of a dished base having a transverse partition defining exhaust-gas intake and discharge chambers, the base also having a flange adapted to 5 rest on the vehicle floor about an opening therein accommodating said base, a gas connection for each chamber, a tubular water jacket having a bottom plate adapted to close the open top of said base and also having 10 at its upper end a hollow header, a plurality of gas tubes running longitudinally through the jacket and connecting the header with said bottom plate, some of said tubes communicating with the said intake 15 chamber and others communicating with said discharge chamber, and means detachably connecting the jacket to the base.

7. In a combined steam heater and exhaust muffler for internal-combustion motor 20 vehicles, the combination of a dished base

having a transverse partition defining exhaust-gas intake and discharge chambers, a gas connection for each chamber, a tubular water jacket having a bottom plate adapted to close the open top of said base and also 25 having at its upper end a hollow header, a plurality of gas tubes running longitudinally through the jacket and connecting the header with said bottom plate, some of said tubes communicating with said intake 30 chamber and others communicating with said discharge chamber, and through bolts passing through said header and certain of the gas tubes and engaging said base and detachably connecting the jacket and header 35 to the base.

Signed at Hoboken, in the county of Hudson and State of New Jersey, this 24th day of March, A. D. 1921.

MAX ZWICKL.
